PAGE 2

Fig. 2

Fig. 3

Fig. 4

FIG. 1 is a top front-perspective view of a copying machine showing our new design;

FIG. 2 is a bottom rear-perspective view thereof, taken from the side opposite that shown in FIG. 1;

FIG. 3 is a front-elevational view thereof with the top lid in raised position; and

FIG. 4 is a top plan view thereof.

The control knob is shaded to indicate contrasting color.

We claim:

The ornamental design for a copying machine, as shown and described.
